(57) CLAIM

The ornamental design for a belted women's swimsuit, as shown and described.

DESCRIPTION

FIG. 1 is a front view of the belted women's swimsuit;

FIG. 2 is a back view of the belted women's swimsuit;

FIG. 3 is a first side view of the belted women's swimsuit; and,

FIG. 4 is an opposite side view of the belted women's swimsuit.

The horizontal broken lines shown on the surface of the swimsuit's mid region represents stitching. All other broken lines shown in the drawings are for environmental structure only and form no part of the claimed design.
